Term of patent 14 years

(Cl. D48—20)

Fig. 1

Fig. 2

Fig. 4

Fig. 3

Fig. 1 is a side elevation of an operating light unit embodying my new design;

Fig. 2 is a view of the carrier and housing portion of the operating light unit which is a view similar to Fig. 1 with parts broken away for convenience of illustration, the vertical support portion being in a different position than Fig. 1;

Fig. 3 is a view showing the carrier and housing portion of the operating light unit looking from either the right or from the left of Fig. 1; and

Fig. 4 is a fragmentary view of the carrier and a cross-sectional view of the housing taken on line 4—4 of Fig. 1.

The essential features of my novel design reside in the portions shown in solid lines.

I claim:

The ornamental design for an operating light unit, substantially as shown and described.
